Primary Examiner — Caron D Veynar*Assistant Examiner* — Mehri Bajoul(74) *Attorney, Agent, or Firm* — Dunlap Bennett & Ludwig PLLC(57) **CLAIM**

The ornamental design for a cover for dumbbell weights, as shown and described.

DESCRIPTION

FIG. 1 is a top front perspective view of the cover for dumbbell weights;

FIG. 2 is a front elevation view thereof;

FIG. 3 is a rear elevation view thereof;

FIG. 4 is a top elevation view thereof;

FIG. 5 is a bottom elevation view thereof;

FIG. 6 is a right elevation view of the cover for dumbbell weights, with the left elevation view being a mirror image thereof; and,

FIG. 7 is a top front perspective view thereof, laid flat.
